UNITED STATES PATENT OFFICE

132,270

DESIGN FOR A GOLF GAME DEVICE

Le Roy Baker, Kansas City, Kans.

Application August 13, 1941, Serial No. 102,827

Term of patent 7 years

To all whom it may concern:

Be it known that I, Le Roy Baker, a citizen of the United States of America, residing at Kansas City, county of Wyandotte, and State of Kansas, have invented a new, original, and ornamental Design for a Golf Game Device, of which the following is a specification, reference being had to the accompanying drawing, forming a part thereof, wherein the figure is a perspective view of a golf game device, showing my new design.

I claim:

The ornamental design for a golf game device, as shown.

LE ROY BAKER.
